UNITED STATES PATENT OFFICE

162,390

COMBINED PRINTER AND DRIER FOR
PLANOGRAPHIC PRINTING PLATES

Robert A. Dalton, Fairfield, Conn., assignor to
Remington Rand Inc., New York, N. Y., a cor-
poration of Delaware

Application June 4, 1949, Serial No. 3,050

Term of patent 14 years

(Cl. D64—11)

To all whom it may concern:

Be it known that Robert A. Dalton, citizen of the United States, residing at Fairfield, in the county of Fairfield and State of Connecticut, has invented a new, original, and ornamental Design for a Combined Printer and Drier for Planographic Printing Plates, of which the following is a specification, reference being made to the accompanying drawing, forming a part thereof.

Fig. 1 is a perspective view of a combined printer and drier for planographic printing plates, showing the new design; and

Fig. 2 is a perspective thereof showing the top, back and left-hand end.

The invention claimed is:

The ornamental design for a combined printer and drier for planographic printing plates, as shown.

ROBERT A. DALTON.
